UNITED STATES PATENT OFFICE.

WILLIAM RUSH, OF CANONSBURG, PENNSYLVANIA.

COMBINATION TOOL.

Application filed December 13, 1922. Serial No. 606,597.

To all whom it may concern:

Be it known that WILLIAM RUSH, a citizen of the United States, residing at Canonsburg, in the county of Washington and State 5 of Pennsylvania, have invented certain new and useful Improvements in Combination Tools, of which the following is a specification.

My invention relates to combination tools, 10 wherein the same may be used as a socket wrench, valve grinder or drill, the tool being so arranged as to be changed in an easy and expeditious manner from one tool to another.

15 The primary object of the invention resides in the provision of such a device that is simple of construction, comparatively inexpensive of manufacture, and highly useful for a large number of purposes.

20 With these general objects in view and others that will appear as the nature of the invention is better understood, the same consists in the novel construction, combination, and arrangement of parts hereinafter more 25 fully described, illustrated in the accompanying drawings, and pointed out in the appended claim.

In the drawings forming part of this application, like numerals of reference indicate similar parts in the several views, and wherein:—

Figure 1 is a side elevational view of a device constructed in accordance with the present invention, the same being shown as 35 employed as a socket wrench.

Figure 2 is a vertical sectional view of the tool shown in Figure 1.

Figure 3 is a side elevational and cross sectional view of the tool, the same being 40 shown as adapted for the reception of a bore or drilling tool.

Figure 4 is an elevational cross sectional view of an attachment whereby the tool may be employed as a bolt holder and nut 45 remover.

Figure 5 is a longitudinal cross sectional view of a specific form of nut engaging socket employed in connection with the present device.

50 Figure 6 is a side elevational view of an attachment for the tool, whereby engine valves may be rotated.

Figure 7 is a fragmentary cross sectional view through the gear casing of the tool.

55 Figure 8 is an elevational view of a ream-

ing tool employed in connection with the present invention, and

Figure 9 is an enlarged fragmentary cross sectional view of one end of the gear casing of my invention.

With particular reference to the drawings, my device contemplates the provision of an open ended hollow casing 1, having a handle 2 formed thereon.

Referring to Figure 9, the ends of the 65 casing 1 have an annular internal shoulder 3 therein for receiving the shouldered edge of cover plates 4. These plates 4 are retained within the ends of the casing by split

spring rings 6 received within channels 7 70 formed in each end of the said casing.

Journaled within suitable openings in the cover plates 4, which openings are slightly off center of the plates are the opposite ends

75 of a rotary shaft 8, one end of which projects outwardly of one of the plates 4 and casing operating handle 9. The shaft 8 has

keyed thereto adjacent one of the plates 4, a large worm gear 10, which gear meshes with a pair of spaced worm pinions 11,

therebeneath, which are keyed to a pair of shafts 12 transversely within the casing and journaled in suitable openings within the cover plates 4. These shafts 12 also have

keyed centrally thereon, other worm pinions 13, intermeshing with a worm gear 14

80 upon the upper end of a pendent shaft 15. This latter mentioned worm 14 rests upon a collar 16, within the casing 1, which collar is formed around an opening 17 in the bot-

90 tom wall of the casing. The casing 1 has externally formed thereon a pendent sleeve or collar encircling the opening 17 therein, and reduced and screw threaded at 19 at its lower end.

95 The shaft 15 projects outwardly of the pendent collar or sleeve 18, and has keyed thereto a thimble 20, which thimble has an angular opening 21 in its bottom wall, and directly beneath the end of the shaft 15.

100 This angular opening of the thimble receives an upper angular end of an annular shaft 22, which shaft is maintained within the opening of the thimble by a spring

pressed dog 23 carried by the thimble and 105 engaging within a notch at the upper end of the shaft.

110 Loosely engaging over the shaft 22 is a tube 24 enlarged at its upper end as at 25 for permitting the engagement of the tube

over the said thimble 20. The upper end of the enlargement of the tube 24 is internally screw threaded as shown, for threaded engagement with the threaded, reduced end 5 17 of the collar 18.

The lower end of the tube 24 is enlarged and threaded at 26 for engaging within an internally threaded nipple 27, upon the top side, and at one end of a right angularly 10 extending housing 28. This end of the housing is open and internally screw threaded for receiving a screw threaded plug 29. The opposite end of the housing has a smaller opening 30 therein, for allowing a 15 shaft 31 to project therethrough, the opposite end of this shaft being reduced as at 32 for engaging within a central socket of a plug 29. Adjacent the inner face of this plug, the shaft 31 has keyed thereto a small 20 bevel gear 33 intermeshing with a similar gear 34 upon the lower end of the before mentioned shaft 22, whereby when this shaft 22 is rotated, a similar movement will be imparted to the shaft 31. The projecting 25 end of the last mentioned shaft has an angular socket 35 formed thereon for the reception of an angular shank 36 of a nut receiving socket 37, or a similar shank 38 of a valve rotating member 39 or still further, 30 the shank 40 of a milling tool 41. These elements are more clearly shown in Figures 5, 6 and 8, and the angular shank of each has a notch 42 therein, for engaging a pivoted dog 43 upon the socket end 35 of the 35 shaft 31, this socket having an opening to allow the head of the dog to pass through for this purpose.

As more clearly shown in Figure 5, the shank 36 of the nut receiving socket 37 has a longitudinal bore 44 extending therethrough for receiving one end of a plunger 45, the opposite end of which carries an angular plate 46 within the socket 37. The plunger 45 is channeled as at 47 for allowing the same to slide beneath a transverse pin 48 in the bore of the socket shank 36. A coiled spring 49 between the plate 46 and inner wall of the socket 37 tends to normally project the plate outwardly to a position as shown, by allowing this plate to move inwardly when a nut is to be received within the socket 37. It will therefore be seen that when a nut is received within the socket, the same may be unscrewed from its bolt and after being entirely unscrewed therefrom, it will be projected outwardly of the socket by the spring pressed plate 46.

From the above description, it will at once be apparent that I have adapted my tool to 60 be readily changed from a socket wrench to a valve rotating tool, or a milling or cutting tool, merely by positioning a desired one of these tool implements which are shown in Figures 5, 6 and 8 in the socket 35 of the shaft 31.

In Figure 3, my tool is shown as being adapted for the reception of boring or drilling implements, and in accommodating this tool for such purposes, a thimble 50 is keyed to the projecting end of the shaft 15, which 70 thimble is formed with a pendent externally threaded skirt portion 51. Within this skirt portion 51, are the usual pivotally secured pendent drill engaging arms 52. Positioned at its upper end, over the said thimble is, 75 what may be termed, a relatively long sleeve 53, internally threaded adjacent its upper end as at 54 for engagement with the threaded skirt portion 51 of the thimble 50. The lower end of this sleeve converges inwardly 80 as at 55 for engaging the lower ends of the drill receiving arms 52 when the sleeve is screwed downwardly upon the thimble 50 and for properly retaining the drill between the ends of these arms. A nut 56 may be 85 provided upon the screw threaded end of the casing collar or sleeve 18, to prevent the marring of these threads when the device is used as a drill.

In Figure 4, I have shown an attachment 90 for my device, whereby the same may be a bolt holding and nut removing tool. This attachment includes the tube 56 internally screw threaded at its upper end for engaging over the reduced, lower, screw threaded 95 end 19 of the pendent casing or sleeve 18. This tube has the reduced portion 57 for receiving a shaft 58, the upper squared end 59 of which engages within the angular opening 21 of the thimble 20 shown in Figure 2. 100 The reduced portion 57 of the tube extends through an opening in an arm 60, which arm has a right angularly bent pendent portion 61 formed thereon. The end of this bent or pendent portion of the arm has 105 an annular flange or head 62 formed thereon, and this head together with the portion 61 extends within a tube or cylinder 63 formed vertically upon one end of an arm 64, which arm extends beneath the first mentioned arm 60 and is of similar dimensions therewith.

As is clearly shown in Figure 4, a portion of the reduced end 57 of the tube 56 extends beneath the opening in the arm 60 115 and is screw threaded for receiving thereon a retaining nut 65, the portion of the end 57 of the tube above the arm 60 having an annular shoulder 66 for close contact with the upper surface of the said arm 60. The shaft 58 also extends beyond the end of the said tube and has keyed thereto an angular sleeve 66, which sleeve has a spring pressed dog 67 for engaging within the notch 47 in the shank of the nut receiving socket 37 shown in Figure 5. The lower arm 64 has an angular opening 68 therein for receiving the shank 69 of a bolt head receiving socket 70. The shank of this socket is also provided with a notch for receiving 120 125 130

the head of a spring pressed dog 71 carried by the arm for firmly retaining the socket therein.

The bolt head and nut receiving sockets are normally maintained in close proximity to each other by a relatively strong coiled spring 72, within the tube or cylinder 63. The lower end of this spring engages upon the head or flange 62 of the 10 pendent portion 61 of the arm 60, the upper end engaging beneath a cap 73 internally screw threaded for engagement with external screw threads on the upper end of the tube or cylinder 63, this cap having a central opening 74 therein for allowing a free 15 sliding movement of the portion 61 of the arm 60.

In view of this latter mentioned construction, it will be readily understood that when 20 the attachment shown in Figure 4, is properly applied to the tool and after the nut engaging socket has been received within the socket of the sleeve 66, the arms 60 and 64 may be sprung away from each other, 25 whereby the bolt head and nut receiving sockets may engage over the head of a bolt and the nut respectively.

Any turning movement of the tool handle 9 will occasion a rotary movement of the 30 shaft 58 for consequently removing the nut from the bolt, the socket 70 preventing the said bolt from turning. In view of the spring 72 within the tube or cylinder 63, the arms 60 and 64 may be so extended as 35 to adapt the attachment for any length of bolt.

It is to be understood that the milling tool shown in Figure 8 is to be used for milling the surface of an engine block or the 40 like at a point adjacent the bolt and nut connections, it being at the present time,

almost an impossibility to properly use a socket wrench for removing the nuts, due to the close proximity of these nuts to the engine blocks. As shown in Figure 8, the 45 milling end of this tube is hollow and has an external milling surface, whereby the same may be engaged over a nut for properly milling the surface of the engine block adjacent the nut for permitting the employment of my socket wrench. 50

While I have herein shown and described the preferred embodiments of the present invention, it is nevertheless to be understood that minor changes may be made 55 therein, without departing from the spirit and scope of the invention as claimed.

What I claim as new is:—

A combination tool, including a driving head having driving means therein, a driven shaft rotatable in the head adapted to be driven at a relatively different speed from the driving means, a socket member 60 removably secured on the outer end of said driven shaft, a tube element removably 65 mounted on the driving head, said tube element having a shaft rotatable therein for removable connection in the socket member on the driven shaft, a housing mounted transversely on the lower end of the tube 70 element, a shaft rotatable in said housing and disposed at an angle to the shaft in the tube element, driving connections between the shaft in the tube element and the shaft in the housing, the shaft in said housing having a socket formed in the end portion thereof, and a work engaging element having a shank for removable engagement in said socket adapted to project from said housing in line with the shaft in the housing. 75 80

In testimony whereof I affix my signature.
WILLIAM RUSH.
